UNITED STATES PATENT OFFICE.

EMIL JAGENBERG, OF DUSSELDORF, GERMANY.

PAPER-BOX MACHINE.

1,120,719.

Specification of Letters Patent.

Patented Dec. 15, 1914.

Application filed August 4, 1914. Serial No. 854,909.

To all whom it may concern:

Be it known that I, EMIL JAGENBERG, a subject of the German Emperor, and a resident of 107 Himmelgeisterstrasse, Dusseldorf, Germany, manufacturer, have invented certain new and useful Improvements in Paper-Box Machines, of which the following is a statement.

In the paper box machine, which is, for example, described in the United States specification 1,001,856 paper boxes are made and by means of a second, similar folding device paper sheets are folded around and gummed to the thus made boxes, while the latter are still on the cores. With such machines it may, now, occur, that for some reason or other the paper feed to the first folding device fails, so that this folding device operates idle and no box is formed on the respective core. When, then, this core reaches the second folding device, which gums the paper sheets around the formed boxes, the paper sheet will be wrapped around the empty core, and gummed to it.

The object of the present invention is to obviate this disadvantage.

The present invention consists in an arrangement which will automatically disengage the feed of the paper to the second folding device, when there is no box on the core, around which the paper sheet would be wrapped.

In the accompanying drawing the present invention has been exemplified, Figure 1 being a side elevation, Fig. 2 a cross section.

The pile of sheets A rests on a plate 3 between the vertical rails 1. These rails 1 are secured to a plate 5, which is guided in a vertical direction by means of guide rods 6 in blocks 7. The plate 5 is vertically reciprocated by means of a double-armed lever 8 and a cam disk 11 fitted to shaft 50. The one end of said double-armed lever engages under a cross piece 9 forming connection between the bottom ends of the rods 6, and the other end of said lever carries a roller 8^a, which rides on the cam disk 11. Above the one edge of the pile of sheets A is journaled a shaft 10, carrying the gum applying and taking off segments and ledges, which shaft is each time intermittently revolved by one revolution by means not shown in the drawing, whereby the known segments 12 and ledges are simultaneously provided with gum by means of a gumming device consisting of the rollers 17, 18, 19.

The plate 3 carrying the pile of sheets is coupled with a toothed rod 20, in the teeth of which engages a pawl 21, which holds down the rod 20 and the plate 3 contrary to the pull of the springs 22. The springs are secured to the plate 5 and to the lower end of the rod 20. The pawl 21 is pivoted to the one arm of a double-armed lever 23, the other arm of which carries a roller 23^a which rides on a cam disk 24, fitted to the shaft 50. In the pawl 21 is furthermore fitted a pin 25, which on the rocking of lever 23 strikes against an inclined surface 26, which is provided on one of the guides 7. Beneath the shaft 10 is journaled a roller 27 in arms 27^a, which are rigidly fitted to a shaft 48. The shaft 48 itself is journaled in the body of the machine. The roller 27 is driven by means of a spur gearing 29, 30 from the shaft 10.

The lever 23 which carries the pawl 21 is provided with a nose a, b around which a hook b engages, when the part 1 is in lowered position. This hook b is keyed to a shaft c journaled in the body of the machine, on which shaft is further fitted a lever d, the free end of which is linked by means of a rod e to a lever f. This lever f is journaled in a bracket 13 and has in its upper end a pin g, which projects through the platen h for the bottom flaps of the box formed on the core i, and can emerge a little on the inside of this platen h. The cores i are movably arranged in known manner (United States specification 1,001,856), so that one after the other will arrive in front of the platen h. The cores are provided with holes j in their face ends, into which the pin g can enter, when the respective core arrives empty in front of the platen h. The bolt 15 carrying the platen is fitted adjustable by means of screws 16 in an arm k, which is pivotally fitted on a pin l in the bracket 28 and is linked to lever n by means of rod m. This lever n is keyed together with lever o to shaft p journaled in the body of the machine. The lever o is linked to a rod 52 which carries at its lower end a fork 53 and a roller 54. The fork encircles the shaft 50 on which is fitted a cam disk, against which the roller 54 rides. On the shaft 44 of lever 23 is also rigidly fitted a second lever q, which is hingedly connected by means of a rod r with a lever s. This lever s, which is journaled on the bracket 58 carries a movable nose t, behind which a lever u

rigidly fitted to shaft 48 can engage, the said lever u being coupled to a lever 49. The lever 49 has at its end a pin 56, which is grasped by the hooked end of rod 47, linked to the handlever 41. This handlever is pivotally journaled on the body of the machine and is coupled by a rod x with a cam lever y journaled on the bracket 51. One of the levers 27^a carries a roller v , which lies in the track of a cam w fitted to shaft 10. Between the gum applying segments 12 engage the stationary strippers 31, the front edges of which are situated close behind the roller 27, and which extend up to close in front of two rollers 32 and 33. These rollers are continuously revolved in opposite directions. Behind the rollers felt plates 34 are provided, over which the cores i pass.

After each revolution the shaft 10 stops in such a position, that the segments and ledges are directed vertically downward. While the shaft 10 is at rest, the rods 6 with the plate 5 are lifted by lever 8 and the cam disk 11, while, however, the pawl 21 holds down the plate 3 with the pile of sheets. Then the recess 24^a in the cam disk passes beneath the roller 23^a on the double-armed lever 23, so that the pawl can rise. In consequence thereof the springs 22 can move the rods 20 with plate 3 and pile A upward. The pin 25 on the pawl 21 which is likewise raised, strikes against the surface 26, whereby the pawl is disengaged from the teeth of the rod 20. The rod 20 is therefore perfectly free and the springs 22 can press the pile of sheets, irrespectively of the number of the latter, and its height against the segments 12 carrying the gum and the ledges on shaft 10. Immediately after the lever 8 lowers the rods 6 with the plate 5 a short distance, and thereupon the rocking of lever 23, the pawl of which 21 reengages with the teeth in the rod 20 moves the plate 3 downward with the pile of sheets. The uppermost sheet of the pile A, however, adheres to the gummed segments 12. Simultaneously with the downward movement of the pile the shaft 10 is revolved by exactly one revolution by means of the gear not shown in the drawing. The sheet adhering to the segments 12 is carried along thereby and pressed by the likewise revolving roller 27 tightly against the gummed segments and ledges on shaft 10, so that it is gummed correspondingly with the surfaces of these parts. The strippers 31 then detach the sheet from the gumming roller and take it between the rollers 32 and 33 which convey it to the folding platens.

Before the roller 10 has completed its revolution, the segments and ledges on it are again gummed afresh by roller 19. If, now, there is no box on the core i arriving in front of the presser platen h , the pin g , 654 which is advanced by the spring z acting

on lever d , can enter into the bared hole j , when the platen h is swung forward. Then the hook b can engage under the nose a on the lever 23 which is still raised with this end. When, then, the roller 23^a on lever 23 reaches the recess, 24^a and tends to lift the pawl, this will be prevented by the hook b , so that the pile of sheets A remains in its lowered position and no sheet can be pulled off from it by the segments 12. 75 Therefore no sheet will be gummed and wrapped around the empty core, so that the latter will not be soiled. By holding down the pawl 21 however, also the plate 5 and the lug t will be held in raised position, so that the pressure roller 27, which has been pressed down by the cam w shortly before the preceding revolution was completed, will likewise remain in its raised position by the lever u remaining engaged with the lug t , so that the gumming roller, which now runs idle, will not be soiled. When, however, there is a folded box on the core i arriving in front of the platen h , the bottom flaps will prevent the pin g entering 90 into the hole j , and the hook b is retained. The pawl 21 can, therefore, rise so that the lug t is drawn from the lever u , and the roller 27 is pressed by the spring 57 acting on the lever u against the gumming roller 95 or against the sheet of paper on the same respectively.

For stopping the machine the handlever 41 is thrown up, whereby the cam lever y bears against lever 23 and thereby prevents 100 the pawl 21 from rising. At the same time the rod 47 pulls with its hooked end the pressure roller 27 from the gumming roller.

I claim:

1. Paper box machine of the character described, consisting of a pile of sheets, means for pulling off the uppermost sheet, a rack, supporting the pile, a pawl engaging in said rack, a lever, on which the pawl is pivoted 110 and adapted to be rocked by suitable means, whereby the pile is raised and lowered, cores, around which the boxes are formed, a pin, in front of which the said cores arrive, holes in the face ends of the cores and 115 adapted for the pin to enter into them when there is no box on the respective core, a presser platen, adapted to push the pin forward, means, connected with the pin for locking the said lever, so that the pawl 120 cannot rise, when the pin can enter into the hole in the core.

2. Paper box machine, consisting of a pile of sheets, a revolving gumming roller for taking off the uppermost sheet, a pressure roller rockably fitted on levers, springs, tending to press the pressure roller against the gumming roller, means for holding the pressure roller in lifted-off position, said means adapted to be disengaged when the 130

pile of sheets rises, means for forcing the pressure roller away from the gumming roller after the uppermost sheet has been completely pulled off the pile.

- 5 3. Paper box machine, consisting of a rising and falling pile of sheets, a revolving gumming roller for pulling off the uppermost sheet, a roller, which presses the drawn off sheet against the gumming roller, a
10 handlever for pulling this pressure roller away from the gumming roller, means for raising and lowering the pile of sheets,

a cam lever coupled to the handlever, adapted to lock said means when the pressure roller is lifted-off, so that the pile can- 15 not rise.

In testimony whereof I have hereunto set my signature in the presence of two subscribing witnesses.
